FILTER FOR PRESSURIZED FLUID

Claude J. Dussardier, Littleton, Colo., assignor to
C. A. Norgren Co., Littleton, Colo.

Filed Oct. 4, 1973, Ser. No. 403,545

Term of patent 14 years

Int. Cl. D23—01

U.S. Cl. D23—4

FIG. 1 is a perspective view of a filter for pressurized fluid showing my new design;

FIG. 2 is a top view thereof;

FIG. 3 is a side elevational view thereof;

FIG. 4 is a bottom view thereof; and

FIG. 5 is an additional side elevational view thereof.

I claim:

The ornamental design for a filter for pressurized fluid, as shown.
